UNITED STATES PATENT OFFICE

CHARLES D. SCHRADER, OF LOGANSPORT, INDIANA

WAXING AND POLISHING DEVICE

Application filed June 6, 1932. Serial No. 615,754.

The object of the invention is to provide a device for either commercial or domestic use to enable the user to first apply wax to a floor surface and thereafter carry out the polishing operation by the simple expedient of inverting the device; to provide a device of the kind indicated which incorporates a wax chamber or magazine that will make wax always available by providing a large source of supply, so that the periodic application of wax may be unnecessary; to provide a waxing device that will effect an even and thin spread of the wax; to provide a construction employing a fabric, such as cheese cloth, on the waxing head for the wax to be forced through and to make the means retaining releasable, so that it may be removed, with the means having the additional function of a bumper to preclude damage in the event of impact of the device with the wall surface or with furniture; and generally to provide a waxer and polisher which is of simple form and therefore susceptible of cheap manufacture.

With this object in view, the invention consists in a construction and combination of parts of which a preferred embodiment is illustrated in the accompanying drawings wherein:

Figure 1 is a view partly in elevation and partly in section of the invention.

Figure 2 is a top plan view.

Figure 3 is a plan view of the brush head with the bristles removed.

Figure 4 is a detail elevational view of a portion of the wall of the wax chamber showing the brush head latch seat.

Figure 5 is a detail sectional view illustrating the connection between the handle and the bail.

Figure 6 is a sectional view on the plane indicated by the line 6—6 of Figure 5.

Figure 7 is an end view of the structure of Figure 5.

The invention comprises a waxing head 10 and a polishing head 11 positioned respectively at the remote ends of a cylindrical member 12 which constitutes a wax magazine or reservoir or chamber. The waxing head 10 is preferably of annular or ring form and

is peripherally grooved, the cylindrical member 12 being received in the eye or opening of the ring. Thus the wax chamber which the cylindrical member defines has its bottom in the plane of the under face of the waxing head and this bottom would be opened were it not for the fact that the fabric 14 which is stretched across the head closes it. The fabric 14 is preferably cheese cloth and may be in one or more layers or plies, depending on how fast it is desired to apply the wax.

The fabric is retained in place by means of the elastic ring 15 which seats in the peripheral groove of the head. The fabric may thus be stretched and retained in such stretched condition, the ring 15 in addition to functioning as a retainer, serving as a bumper to prevent impact of the head with wall surfaces or the furniture when the head is moved over the floor surface.

Wax application is had by charging the cylinder 12 with the desired amount of wax which is disposed directly on top of the cloth or fabric 14 and this wax is fed through the latter by means of a pressure block 16 made preferably of cast iron and of sufficient thickness to provide the necessary weight, the block being freely movable in the cylinder vertically.

The handle 17 by which movement of the head over the floor surface is effected is connected with the block through the instrumentality of a bail 18 which has a swinging mounting with a bracket plate 19 secured to the block, the bail carrying collar 20 disposed in the clearance slot in the bracket plate, so that there will be no relative lateral movement between the block and bail.

Clearance slots 21 are provided at diametrically opposite sides of the cylinder and open at the top of the latter and in these slots the bail moves to permit direct application to the wax contents of the weight of the block. By opening at the upper end of the cylinder, the slots permit removal of the block without disconnecting it from the bail.

The polishing member 11 acts as a closure to the upper end of the cylinder and is removably latched to the latter, being provided with brackets 22 in which spring actuated

latch pins 23 are mounted. These latch pins are formed with shouldered portions 24 which engage the bottoms of keyhole slots 25 when the latch pins are in latching position. 5 In unlatching, the pins are released by pulling on the finger rings 26, when the shank portions of the latch pins are in position to pass through the legs of the keyhole slots, when the polishing head may be lifted off or 10 disengaged from the cylinder.

The polishing head is provided with a peripheral binding 27 of rubber or the like and carries a block 28 or the like in which the bristles 29 are mounted.

15 To effect connection between the bail and handle, a ferrule 30 is mounted on the lower end of the handle and the arms of the bail have the extremities bent as of 31 inserted in the protruding end of the ferrule where 20 the outturned ends 32 pass through openings or holes in the ferrule. A key member 33 inserted in the protruded end of the ferrule between the bent terminals of the bail and pinned to the ferrule as indicated at 34, serves 25 to maintain the engagement of the bail with the ferrule.

The polishing head is provided at diametrically opposite sides with bail seats 35 in which the bail engages when the device is 30 inverted for polishing.

The latch pins provide for readily removing the polishing head and when this is done, the cylinder may be charged with wax after removing the pressure block. A half or full 35 box of wax, having been placed in the cylinder, the pressure block is replaced and the polishing head reattached. The waxing operation may then be proceeded with, the head being moved back and forth across the floor 40, through the instrumentality of the handle 17 and the block 16 applying pressure to force the wax through the fabric or cloth 14. The waxing operation having been completed, polishing is accomplished by inverting the 45 head to dispose the polishing head downwardly when the weight of the block is transferred direct to the head by the bail engaging seats 35 in the latter. The handle then serves as a means for removing the head to 50 carry out the polishing operation as it did the waxing operation.

What is claimed as new and useful is:

1. A floor waxing device comprising a waxing head formed with an open bottomed 55 wax receiving chamber, a fabric stretched across the head and closing the chamber at the bottom, a weight slidably disposed in the chamber for the application of pressure to any wax contents thereof, and a handle to 60 impart sliding movement to the waxing head, the wax chamber having a removable closure disposed above said weight provided with bristles on its top face to constitute a

polishing brush, the handle being swingingly connected to the head to permit its inversion and use of the bristles.

2. A polishing device comprising a polishing head formed with a centrally disposed open bottomed cylindrical wax chamber, a fabric stretched across the under face of the head and closing the bottom of the wax chamber, a pressure block dimensional according to the chamber and slidably mounted therein on any wax contents of the chamber, a handle having a swinging mounting with the pressure block, a removable closure for the upper end of the wax chamber, and said closure on its upper face being provided with bristles, the waxing head being invertible to dispose the bristles downwardly for polishing.

3. A polishing device comprising a ring like polishing head formed with a centrally disposed cylindrical wax receiving chamber open at its bottom, a fabric stretched across and peripherally secured to the head and closing the bottom of the chamber, a pressure block slidably mounted in the chamber for the application of pressure to the wax contents thereof, a handle, a bail having a swinging connection with the pressure block and passing through vertical slots in the wall of the wax chamber, the bail being connected with the handle, and a bristle carrying member releasably connected with the wax chamber and closing the latter at the top, the connection between the bail and pressure block permitting inversion of the head to dispose the bristle carrying member downwardly for polishing.

4. A polishing device comprising a ring like polishing head formed with a centrally disposed cylindrical wax receiving chamber open at its bottom, a fabric stretched across and peripherally secured to the head and closing the bottom of the chamber, a pressure block slidably mounted in the chamber for the application of pressure to the wax contents thereof, a handle, a bail having a swinging connection with the pressure block and passing through vertical slots in the wall of the wax chamber, the bail being connected with the handle, and a bristle carrying member releasably connected with the wax chamber and closing the latter at the top, the connection between the bail and pressure block permitting inversion of the head to dispose the bristle carrying member downwardly for polishing, the latter having seats for engagement with the bail in the inverted position of the head to transfer the weight of the pressure block directly to the bristle carrying member.

In testimony whereof I affix my signature.
CHARLES D. SCHRADER.
